UNITED STATES PATENT OFFICE.

ALLEN W. ROSE AND CHARLES A. CHEEVER, OF NEW YORK, N. Y.; SAID ROSE ASSIGNOR TO SAID CHEEVER; SAID CHEEVER ASSIGNOR TO HIMSELF AS TRUSTEE.

ELECTRIC SPEAKING-TELEPHONE.

SPECIFICATION forming part of Letters Patent No. 252,142, dated January 10, 1882.

Application filed November 12, 1880. (No model.)

To all whom it may concern:

Be it known that we, ALLEN W. ROSE, a citizen of the Dominion of Canada, residing in the city, county, and State of New York, and CHARLES A. CHEEVER, a citizen of the United States, also residing in New York city aforesaid, jointly have invented certain new and useful Improvements in Electric Speaking-Telephony, of which the following is a specification.

Our invention is based upon and constitutes an improvement upon certain new and useful improvements in electric telephony made by the aforesaid Rose, the distinguishing characteristic of which is the suspension of magnetic filings in the magnetic field of a speaking-telephone, through which field a galvanic current passes.

In another application made by us jointly for Letters Patent of the United States we have shown an improvement upon the said ROSE's invention, which improvement consists in suspending the filings in a magnetic field through which the current, when the telephone is used as a receiver, does not necessarily pass, the magnetism acting inductively on the filings in such case.

The object of our present invention is to dispense with a permanent magnet or the equivalent core of an electro-magnet, substituting therefor the inductive action of an ordinary coil or helix included in an ordinary electric circuit.

The subject-matter claimed is hereinafter specified.

Our invention may be modified in various ways, of which the accompanying drawings furnish the best illustrations now known to us.

Figure 1 represents a central longitudinal section through an apparatus adapted for operation both as a receiver and as a transmitter, the current flowing from the ground through the battery B over the line l , and through a helix or flat spiral, C, of ordinary insulated wire, through the wire l' , which is connected with the sheet C' of conducting material, preferably non-magnetic—such, for instance, as tin-foil or

sheet-brass. The current flows through this coil and conducting-surface, magnetizes the filings or powder F of some magnetic material—such as iron, steel, aluminium, cobalt, or nickel—in the magnetic field between the conducting-surface C' and the diaphragm D, causing the filings to stand upright and establish connection with the plate or diaphragm D, which is of non-magnetic conducting material, connecting with the line-wire L.

In operation as a transmitter the diaphragm is vibrated by sound-waves, which in turn produce correlated changes or variations in the filings, and consequently in the resistance of the circuit or the strength of the current flowing therethrough, which variations may be reproduced in any of the well-known forms of receivers connected with the line wire, and thus accurately reproduce articulate speech as to tone, pitch, and quality. If two such instruments as those above described were placed upon the line, the variations in the strength of the current caused by the sound-vibrations of the transmitter would be accurately reproduced upon the other, the apparatus being equally well adapted for use as a transmitter and as a receiver. When used as a receiver the current passes from the line through the diaphragm and filings to the conducting-surface C', wire l' , coil C, and wire l , to the ground, or, in other words, in a direction exactly the reverse of that in which it passes when acting as a transmitter. The variations in the strength of this current caused by the sound-vibrations of the transmitter produce corresponding variations in the magnetic field of the receiver by passing through its helix C, and thus cause correlated movements in the filings, which are correspondingly reproduced upon the diaphragm and converted into sound-waves.

In order to keep the magnetic filings in a proper condition, we prefer, though it is not necessary, to connect the diaphragm D and conducting-surface C' by a substance of high resistance relative to the filings—such, for instance as a ring or slip of oil-stone, O, pro-

vided with a conducting-surface of carbon or plumbago, or of a strip of carbon or other paper covered with powdered plumbago.

Fig. 2 represents a vertical central section 5 through the apparatus organized for transmission only, the coil C in this case being provided with a local battery, L B, for keeping it charged. The line passes from the ground and main battery through the wire l to a conducting surface or plate, C', similar to that above described, through the magnetic filings F and diaphragm D to the line-wire L.

Fig. 3 represents a vertical central section 15 through one form of our improved apparatus organized for use as a receiver only. The current from the transmitter passes through the line-wire L to the coil C, and thence to the ground through the line l. The variations in the strength of the current thus transmitted 20 are reproduced upon the filings in the manner mentioned above. It is obvious that under this organization it is immaterial whether C' be a conducting-surface or not. In this instance a ring, b, interposed between the surface 25 face C' and the diaphragm, prevents the escape of the filings when not subject to magnetic action, and some equivalent protection is preferably employed in all of the forms of the apparatus. We find it advantageous in this 30 form of apparatus to employ a local circuit provided with a local battery, L B, to keep the coil charged, as described in Fig. 2; but to prevent the short-circuiting of the current from the transmitter we interpose a resistance, R h, 35 greater than that of the coil employed in the local circuit, and a switch, S, of ordinary construction, may be employed to throw this line out of circuit when required.

Fig. 4 represents a vertical central section 40 through an apparatus adapted for operation both as a receiver and as a transmitter, in connection with an induction-coil and a locally-charged circuit such as above described. We may remark here that any of the instruments 45 herein described could be used in connection with an induction-coil in well-known ways, and with or without a separate local circuit for charging the coil.

Fig. 4 shows the primary wires of an induction-coil, (in which is included the local battery L B' in the ordinary way of telephonic transmission,) connected one with the conducting-surface C' and the other with the diaphragm D, the circuit being completed through the 55 filings. The secondary circuit of the induction-coil to which the line-wire is connected passes through the inducing-coil C, in the usual well-known way, to the ground. This inducing-coil is shown as composed of two separate coils, 60 each in the form of a flat spiral, and one placed upon the other. We prefer to carry the line-wire connections through the coil nearest the conducting-surface C', while the other is included in the charging-circuit provided with 65 the local battery L B, thus obviating the necessity for the employment of the resistance

coil or switch incident to the construction shown in Fig. 3. As the coils are separate, there is no danger of short-circuiting the line-current. The arrangement of the two coils 70 may obviously be varied in well-known ways—such, for instance, as winding them alternately in the same plane, so as to constitute a double spiral.

Fig. 5 shows a section through a coil of this 75 latter construction.

We do not claim herein the method of operation of the devices described, nor the combination of the electric circuit, an inducing-helix without a core included therein, a local battery included in a local circuit connected with the helix, a resistance in said local circuit to prevent short-circuiting the main line, a diaphragm, and magnetic filings interposed between the inducing-helix and diaphragm, as 80 these subjects-matter will be embodied in another division of this application.

We claim as our invention—

1. The combination, substantially as herein set forth, of an electric circuit, a battery, an 90 inducing-helix, a non-magnetic conducting-surface, a diaphragm, and magnetic filings interposed in the magnetic field between said conducting-surface and diaphragm.

2. The combination, substantially as herein 95 set forth, of an inducing-helix, a conducting-surface, a diaphragm, magnetic filings interposed between the helix and diaphragm, and a high resistance between the diaphragm and conducting-surface to maintain the continuity 100 of the magnetic circuit.

3. The combination, substantially as herein set forth, of the local circuit, its battery, the inducing coil without a core in the local circuit, and the magnetic filings, whereby the 105 filings are maintained in a constant magnetic field.

4. The combination, substantially as herein set forth, of an electric circuit, a conducting-surface, a diaphragm, and magnetic filings interposed between the conducting-surface and diaphragm, with an inducing-coil and an independent battery and local circuit for keeping 110 the coil charged.

5. The combination, substantially as herein 115 set forth, of an electric circuit, a battery, an inducing-helix without a core in said circuit, a diaphragm, and magnetic filings interposed between the inducing-helix and diaphragm, the filings being acted upon inductively by 120 the helix and the diaphragm being vibrated by the movement of the filings.

6. The combination, substantially as herein set forth, of two independent but adjacent inducing-coils without cores, a diaphragm, and 125 magnetic filings interposed between said diaphragm and coils.

7. The combination, substantially as herein set forth, of a local circuit, its battery, an inducing-coil without a core for maintaining a 130 constant magnetic field, a conducting-surface, a diaphragm, magnetic filings interposed be-

tween the helix and diaphragm, a local battery in the primary circuit of an induction-coil, in which primary circuit the magnetic filings are included, the secondary helix of said induction-coil constituting a portion of the line-wire, and an independent inducing-coil, also included in the line-wire, in proximity to the local inducing-coil.

In testimony whereof we have hereunto subscribed our names this 22d day of October, A. D. 1880.

A. W. ROSE.
CHAS. A. CHEEVER.
